UNITED STATES PATENT OFFICE.

LAURA A. HANES, OF TIFFIN, OHIO, AND VERNE D. HANES, OF JACKSON, MICHIGAN.

FOLDING HEM ADJUSTER.

Application filed October 31, 1927. Serial No. 230,160.

This invention relates to new and useful improvements in folding hem adjusters.

One object of our invention is to provide a device of this character which is simple and economical in construction, very durable in use and extremely easy to operate.

A further object of our invention is to provide a hem adjuster that may be folded into compact form when not in use to facilitate transportation and storage.

With the foregoing and other objects in view that will appear as the nature of our invention is better understood, the same consists in the novel features of construction, combination and arrangement of parts illustrated in the accompanying drawings and more particularly pointed out in the appended claims.

In the accompanying drawings, which are for illustrative purposes only and are therefore not drawn to scale:

Figure 1 is a front elevation of our device ready for use.

Figure 2 is an edge view.

Figure 3 is a view similar to Figure 1, with the measuring and marking elements in folded position.

Figure 4 is a plan view.

Figure 5 is a vertical transverse section, taken on line 5—5 of Figure 2.

Referring to the drawings for a more particular description of our invention and in which drawings like parts are designated by like reference characters throughout the several views, our device comprises a flat relatively narrow rectangular oblong base 1, preferably of wood, formed in its upper face near one end with a transverse groove 2, which extends across the entire width of the base.

Our device further comprises a pair of measuring and marking elements 3 and 4, respectively, in the form of straight flat elongated wooden strips, as shown. The face of the measuring strip 3 is marked off or graduated, as at 5, into inches and fractional parts thereof, while the marking strip 4 is perfectly plain. The aforesaid elements 3 and 4 are arranged diagonally opposite each other, that is to say, the marking strip is arranged slightly behind and in spaced relation with the measuring strip and with its inner side edge in vertical alinement or registration with the adjacent side edge of the measuring strip.

The strips 3 and 4 are secured at their lower

ends to and carried by the cross piece or yoke 5', the bottom edge 6 of which fits in the transverse groove 2 when the hem adjuster is in use. The yoke 5' is held in removable position but against casual displacement in the groove 2 by the straight spring wires 7 and 8 which are arranged along opposite side edges of the base 1 and are formed at opposite ends with right-angularly bent portions 9 and 10 which fit in corresponding recesses or sockets 11 and 12, formed in the opposite ends of the yoke and the opposite side edges of the base, respectively. The spring wires 7 and 8 are secured to the base by the staples 13 which straddle said wires and penetrate the side edges of the former. It will be noted that the rear ends 14 of the spring wires extend in a horizontal plane while the major forward portions 15 extending between the staples and the extreme front ends of the wires, are disposed at a moderate upward inclination. This produces the required tension on the yoke sufficient to hold the same in position in the groove in the base under normal conditions but the yoke with the measuring and marking strips carried thereby may be lifted out of the aforesaid groove against the tension of the spring wires and folded flatwise against the base 1. This renders the device into compact form and facilitates storage and transportation.

In practice, the device is placed in position on the floor beneath the skirt or other garment, the hem of which is to be gauged in relation to its height from the floor. The bottom of the skirt is then placed between the measuring and marking strips with the former situated on the outside and the latter serving as a support against which pressure may be applied with pencil or chalk. The person wearing the garment, the length of which is being gauged, turns as the marking process proceeds until the garment has been marked completely around. Both length of skirt and depth of hem may be marked at the same time, thus saving time and labor. When the garment has been marked completely around by chalk or pencil dashes at frequent intervals, the same may be removed from the person wearing it, the surplus fabric trimmed away and the hem turned up and sewed.

When folded the device may be laid on a table or across the lap to serve as a gauge

or rule in cutting bands or bias pieces or it may be used as a ruler in measuring lengths of goods, its folding construction being such that it lies flat and takes up comparatively little room on the sewing table.

Lightness and simplicity of construction render the device extremely easy to handle when in use and at the same time make it susceptible to home or hand decoration with 10 enamel or paint and thus enhance its possibilities as a gift.

From the foregoing description taken in connection with the drawings, it is thought that the construction, operation and advantages of our invention will be readily understood without requiring a more extended explanation.

Having described our invention, what we claim as new and desire to secure by Letters 20 Patent, is:

1. In a device of the character described, a base provided in its face with a transverse groove, a cross piece or yoke adapted to seat in said groove, measuring and marking strips 25 carried by said yoke and resilient means for

yieldably holding the yoke in said groove against casual displacement.

2. In a device of the character specified, a base provided in its face with a transverse groove, a cross piece or yoke adapted to seat 30 in said groove, measuring and marking strips carried by said yoke and spring wires for yieldably holding the yoke in said groove against casual displacement.

3. In a device of the character specified, a base provided in its face with a transverse groove, a cross piece or yoke adapted to seat 35 in said groove, measuring and marking strips carried by said yoke and spring wires for yieldably holding the yoke in said groove 40 against casual displacement, said spring wires comprising straight horizontal rear end portions and straight upwardly inclined front portions engaging the ends of the yoke and means for securing the spring wires to 45 opposite sides of the base.

In testimony whereof we affix our signatures.

LAURA A. HANES.
VERNE D. HANES.
